United States Patent

Des. 238,647
Patented Feb. 3, 1976

238,647

CUP

Gerald Gulotta, New City, N.Y., assignor to
Block China Corporation, New York, N.Y.

Filed Dec. 20, 1973, Ser. No. 426,896

Term of patent 14 years

Int. Cl. D7—01

U.S. Cl. D7—9

FIG. 1

FIG. 2

FIG. 3

FIG. 5

FIG. 4

FIG. 6

FIG. 1 is a top plan view of a cup showing my new design;

FIG. 2 is a side elevational view thereof;

FIG. 3 is an end elevational view thereof;

FIG. 5 is an end elevational view taken from the direction opposite to that of FIG. 3;

FIG. 6 is a cross-sectional view taken on the line 6—6 of FIG. 1.

I claim:

The ornamental design for a cup, substantially as shown.
